UNITED STATES PATENT OFFICE.

ARTHUR BIDDLE, OF TRENTON, NEW JERSEY, ASSIGNOR TO UNITED PRODUCTS CORPORATION OF AMERICA, A CORPORATION OF DELAWARE.

FIRE-EXTINGUISHING COMPOSITION.

No Drawing.

Application filed July 7, 1920. Serial No. 394,453.

To all whom it may concern:

Be it known that I, ARTHUR BIDDLE, a citizen of the United States, and a resident of the city of Trenton, county of Mercer, 5 State of New Jersey, have invented certain new and useful Improvements in Fire-Extinguishing Compositions, as fully described in the following specification.

The invention relates to a composition of 10 matter or a chemical compound containing ingredients or elements adapted, when chemical reaction occurs, to give off a fire extinguishing gas and to produce a large quantity of bubbles forming a foam of high viscosity and containing such gas, the foam adapted to form a blanket between the combustible substance and the supporter of combustion.

Among the objects of the invention is to 20 utilize the waste or by-product liquid of paper pulp mills in connection with other suitable chemicals adapted to react to produce or form a foam of high viscosity adapted when properly applied to prevent and extinguish fire, particularly in oil tanks, although the same is applicable for preventing and extinguishing fires in other relations.

In the manufacture of paper from wood pulp, there are generally two processes employed, one an alkaline process known as 30 the "soda process" and the other an acid process known as the "sulphite process." In practising either of said processes, there is produced a by-product heretofore of little 35 or no commercial value, generally called "glutrin" or "pulp liquor." That produced by the paper pulp process first above referred to is usually called "soda glutrin" and that produced by the second, "sulphite glutrin."

Both "glutrins" are heavy viscous liquors, the viscosity of which may be increased by evaporation.

Other processes are in use for obtaining 45 wood pulp from which like by-product liquors are obtained, but the above-mentioned processes will serve as illustrations for disclosure of the invention. It is to be understood, however, that the invention is 50 not to be limited to the particular liquors mentioned herein, but such other by-product liquors obtained from the manufacture of wood pulp and similar manufactures are of utility in combining the suitable chemicals

to produce the result obtained by the herein disclosed invention.

Heretofore the extinguishment of fires, particularly in large oil tanks, has been very difficult. The usual mediums of fire extinguishing, such as water, is of no use 60 for such purpose; in fact, water has a tendency to spread the fire. Discovery has been made, however, that a fire extinguishing foam may be produced by combining two portions of chemicals; one portion being a 65 solution of an extract of licorice root and sodium bicarbonate and the other portion being an acid, usually sulphuric acid. Frequently, the first portion mentioned may include soapy solutions, as well as glues of 70 various kinds so as to form a saponified and viscous mass, of bubbles upon the reaction of the chemicals. The extract and the soap or glue solutions are expensive, in that they require a large amount of reacting chemicals to secure the desired result.

By my invention, however, I have discovered that a very viscous foam may be formed which will have such tenacity and durability that the upward rush of the flames will not 80 readily destroy the blanket of foam poured upon the oil surface and in that respect the blanket will be more effective to cut off the supporter of combustion than in the case where the foam is weak and readily torn 85 apart or broken up by the upward rush of the hot gases or flames. I make use of a by-product liquor which is cheap; in fact, is a drug on the market, and with which suitable chemicals, if desired, may be mixed to 90 produce the desired reaction to cause the foam to be formed.

In the "soda" process, the liquor obtained is of an alkaline reaction, while that obtained from the "sulphite" process has an 95 acid reaction. I have found that by mixing an excess of liquor from one process with liquor of the other process a reaction will occur between the alkalis of one liquor and the acid in the other liquor sufficiently to 100 cause an evolution of non-combustible gas, which will be enclosed in myriads of bubbles in the materials of the liquors and form a heavy, viscous and thick foam which may be poured over or forced upon the surface 105 of the material that is burning. This foam is viscous and it may be projected from a nozzle upon the walls and ceilings of the

building to which it will cling or adhere to form a blanket, separating the air from the article or surface that is burning. If a more active reaction is desired, where the excess chemicals contained in the liquor is not sufficient, suitable chemicals may be added, as for example, in the soda liquor, bicarbonate of soda may be added, and in the sulphite liquor, sulphuric acid may be added, 5 in desired proportions or amounts, and the reaction will be more complete, thus liberating a larger quantity of carbonic acid gas, or other non-combustible gas, to produce a larger amount of foam.

10 15 In the event of using merely one of the liquors, such as the soda liquor or "glutrin," the same, in the state obtained from the pulp mills, may be placed in a receptacle, and, upon the occurrence of a fire, an acid may 20 be mixed therewith in order that the latter may react with the alkalis of the "glutrin" and produce a mass of bubbles and foam as above mentioned. Any suitable acid may be used and while I prefer the use of sulphuric 25 acid because of its greatest activity, other acids, such as nitric, hydrochloric, acetic, boric and lactic acids may be used as desired. I have also found that the sour whey or milk which contains lactic acid formed 30 from lactose or milk sugar, is a very economical agent to be used. Vinegar also is of utility, as it contains mainly acetic acid and for a mild acid is of important utility. Salts of these acids and similar acids, may 35 also be used. It has also been found that a very satisfactory result will be obtained if an excess of the gas bearing chemical, such as the carbonates and bicarbonates of sodium, may be added to the soda liquor when 40 the foam is to be formed.

45 In the case of using the sulphite liquor or "glutrin" for extinguishing purposes, the same may be stored in a suitable container with its acid chemicals used in obtaining such liquors and upon the occurrence of a fire, may be mixed with a suitable alkaline agent or chemical which will react with the chemicals of the liquor to produce carbonic acid gas or other non-combustible gases.

50 Among such alkaline substances are sodium bicarbonate, sodium carbonate, marble dust, and other carbonates and bicarbonates, principally of magnesium, barium, calcium, and certain natural forms of these chemicals, 55 such as limestone, dolomite, or magnesite, the sodium bicarbonate being the most active and preferable when a large capacity reaction is desired. The strength and the amount of these chemicals or compounds 60 may be determined upon the particular strength desired and amount of gas to be produced, as well as the viscosity of the foam desired. An acid salt that has been found to give satisfactory increased acidity to the liquor, is acid sodium sulphate which

is also a by-product of the manufacture of sulphuric acid and is also very economical on account of its low cost.

65 While the liquors referred to above are heavy and viscous, I have found, in some cases where the liquor is more or less diluted or greater viscosity and tenacity of the foam bubbles is desired, that a foam with improved fire proofing quality may be obtained by adding certain constituents, such as proteinous matter, glue or casein dissolved in an alkali, starch, flour, gums, glucose, silicate of soda, soaps, or saponified matters, and certain residue liquors given off in the treating of sugar cane and sugar beet, all of which 70 contain more or less proteinous and similar matters that greatly aid in making the foam viscous and durable. In the event of using casein or silicate of soda, it is preferable that the same should be added to the gas bearing 75 solution, that is, the solution having the carbonates, bicarbonates and alkaline substances, since acid solutions have a tendency to precipitate casein and sodium silicate, but the other substances may be added to either 80 the alkaline or acid liquor, that is, the "soda glutrin" or "sulphite glutrin" respectively.

85 In the use of the above chemicals, any suitable mechanical means may be used to contain the chemical portions until the occasion for mixing them together arises and any suitable means may be used to bring the same together to cause a chemical reaction whereby gases are formed, the foam produced and poured or forced over the surface 90 of the burning material. A convenient means for this may comprise a pair of separate containers, in one of which may be placed the "soda glutrin" and in the other, an acid, such as sulphuric acid, and upon the 95 occurrence of a fire, these liquors and substances, conducted by suitable piping, may be forced, as by pumps, to a common point or meeting place in a large conduit where the chemicals will react and produce the 100 foam and be ejected or projected therefrom upon the surface of the oil or other substance. If the "sulphite glutrin" be used, the same may be placed in one container and the alkali, such as bicarbonate of soda, may 105 be placed in the other container, such portions being forced through suitable conduits to a meeting point and caused to mix in a large conduit from which the foam produced therein may be forced over the surface 110 of the oil or like material. When the mixture takes place, carbonic acid gas or other non-combustible gas is evolved from the alkali and gas bearing chemicals. When 115 using soda "glutrin" the gas is produced from the chemicals forming part of the soda liquor or "glutrin," and when using "sulphite glutrin" the gas is evolved from the chemical mixed with said "glutrin" as said chemicals react with the acids mixed with 120

125 130

said "glutrin." As the dissolved substances of the liquors are viscous, the entrapped gas or bubbles thereof form a heavy foam which, when applied to any surface, will shut off 5 the oxygen or other supporter of combustion and will thereby stop or prevent a continuation of the burning thereof.

When using the soda liquor, its viscosity and the carbon dioxid gas content thereof 10 may be first determined and if the gas content thereof when liberated be insufficient to increase the liquor to from 5 to 10 times its original volume, gas bearing chemicals, such as previously mentioned, may be added to 15 strengthen its properties as above indicated.

I have further found that the extinguishing properties of the foam may be enhanced by the inclusion, in either or both liquid portions, a suitable quantity of carbon 20 tetrachlorid. As an example, the adding of from $\frac{1}{2}$ to 20 parts of carbon tetrachlorid to about 100 parts of either or both solutions, to be mixed together, greatly increases the extinguishing properties of the foam. The 25 carbon tetrachlorid, during the gas and foam formation, enters in the bubbles thereof and when subjected to heat vaporizes into a heavy gas blanket thereby, with the foam itself, forming a sort of double blanket for 30 excluding the supporter of combustion.

While I have illustrated a few compounds or mixtures of chemicals in accordance with my invention, it is to be understood, however, that the invention is not limited to the 35 particular ingredients or compositions mentioned, but that other and equivalent substances may be used as do not depart from the spirit of the invention and the scope of the appended claims.

40 Having thus described my invention, what I claim and desire to protect by Letters Patent of the United States, is:

1. A fire extinguishing compound consisting of two solutions which when mixed produce a viscous foam non-supporting to combustion, one of said solutions comprising "sulphite glutrin" having an acid reaction, and the other of said solutions being an alkaline solution.

50 2. A fire extinguishing compound consisting of two solutions which when mixed produce a viscous foam non-supporting to combustion, one of said solutions comprising "sulphite glutrin" having an acid reaction, and the other of said solutions comprising 55 an alkaline "glutrin."

3. A fire extinguishing compound consisting of two solutions which when mixed pro-

duce a viscous foam non-supporting to combustion, one of said solutions comprising a 60 "sulphite glutrin" having an acid reaction, and the other of said solutions comprising a "soda glutrin."

4. A fire extinguishing compound consisting of two solutions which when mixed produce a viscous foam non-supporting to combustion, one of said solutions being an acid solution, and the other of said solutions comprising a "soda glutrin" having an alkaline reaction, a gas producing chemical, and a 70 substance imparting viscosity thereto.

5. A fire extinguishing compound consisting of two solutions which when mixed produce a viscous foam non-supporting to combustion, one of said solutions being an acid 75 solution, and the other of said solutions comprising "soda glutrin" having an alkaline reaction, and a chemical for producing a non-combustible gas, one of said solutions also containing a substance for increasing 80 the viscosity thereof.

6. A fire extinguishing compound consisting of two solutions which when mixed produce a viscous foam non-supporting to combustion, one of said solutions comprising a 85 "sulphite glutrin" having an acid reaction, and the other of said solutions comprising an alkaline solution, and a chemical for producing a non-combustible gas dissolved 90 therein.

7. A fire extinguishing compound consisting of two solutions which when mixed produce a viscous foam non-supporting to combustion, one of said solutions comprising a 95 "sulphite glutrin" having an acid reaction, and the other of said solutions comprising an alkaline solution, and a chemical for producing a non-combustible gas dissolved therein, one of said solutions also containing a substance for increasing the viscosity 100 thereof.

8. A fire extinguishing compound consisting of two solutions which when mixed produce a viscous foam non-supporting to combustion, one of said solutions comprising a 105 "sulphite glutrin" having an acid reaction, and the other of said solutions being an alkaline solution, one of said solutions also containing a chemical for producing a non-combustible gas, and one of said solutions 110 also containing a substance for increasing the viscosity thereof.

In witness whereof, I have hereunto set my hand this 6th day of July, 1920.

ARTHUR BIDDLE.
